H. ROSS

Lubridator

N° 41,785.

Patented March 1, 1884.

UNITED STATES PATENT OFFICE.

ROBERT ROSS, OF BETHLEHEM, PENNSYLVANIA.

IMPROVEMENT IN LUBRICATORS.

Specification forming part of Letters Patent No. 41,785, dated March 1, 1864.

To all whom it may concern:

Be it known that I, ROBERT ROSS, of Bethlehem, Northampton county, Pennsylvania, have invented an Improved Oil-Cup; and I do hereby declare the following to be a full, clear, and exact description of the same, reference being had to the accompanying drawings, and to the letters of reference marked thereon.

My invention consists of an oil-cup constructed in the peculiar manner fully described hereinafter, so that the oil may be admitted to a reservoir, and discharged from the same to the object to be lubricated by the manipulation of a single handle, and without the aid of the complex system of stop-cocks used in connection with ordinary oil-cups.

In order to enable others skilled in the art to make and use my invention, I will now proceed to describe its construction and operation.

On reference to the accompanying drawings, which form a part of this specification, Figure 1 is a vertical section of my improved oil-cup; Fig. 2, a sectional plan on the line 1 2, Fig. 1; and Fig. 3, a sectional plan on the line 3 4, Fig. 1, the cup being in this instance inverted.

Similar letters refer to similar parts throughout the several views.

The body of the cup consists of a chamber or reservoir, A, which has at the top a hollow projection, a, and at the bottom a hollow projection, b. To the lower projection, b, is screwed the branch B, in which is a chamber for the reception of a hollow block, C, the latter resting on the spiral spring c and fitting snugly, but so as to have a free vertical movement in the chamber. In the lower end of the branch B is an opening, d, this end of the branch being secured to the cylinder, steam-chest, or such other part of a steam engine as requires frequent lubrication. Into the projection a is screwed the hollow spindle D, and onto the same projection is screwed a cap, E, forming a gland or stuffing-box of a character well known to those familiar with the construction of ordinary oil-cups.

The screw-spindle D is furnished with a handle, F, and is surmounted with a cup, G, which is divided into an upper receptacle, x, and beneath this a chamber, y, by the parti-

tion e, from the center of which a tube, f, projects into the hollow spindle D.

Openings g are made in the sides of the cup below the partition for a purpose described hereinafter.

The lower end of the spindle D is ground, so as to form a seat for the end h of the rod H, the lower end of which is enlarged, and rests upon the block C, the enlarged end being formed into a valve, h', which is ground to a seat formed on the hollow projection b, the diameter of the rod being somewhat smaller than that of the opening in the said projection b.

On the under side of the valve h' is a small chamber, from which radiate several grooves, i, best observed on reference to Fig. 3.

When the reservoir A has to be replenished with oil, the handle F is so turned as to unscrew the spindle D to a limited extent, thereby elevating the lower end of the spindle free from the end of the rod H, and permitting the oil, which has passed from the receptacle x and through the tube F into the interior of the spindle D, to flow through the annular space between the end of the spindle and rod H into the reservoir A. Before the oil could gain this access to the reservoir, however, the valve h' on the lower end of the rod H had closed to its seat, for as the hollow spindle D rises the rod H must follow, owing to the action of the spiral spring on the block C. As the oil flows into the reservoir, therefore, in fact before the oil begins to flow into the reservoir, the steam is excluded therefrom by the valve h'. When the oil has to be discharged from the reservoir, the handle F is turned in a contrary direction, so as to lower the spindle D, which now bears upon the top of the rod H, and effectually bars the passage of the oil to the reservoir, the turning of the handle F being continued, so as to depress the rod H and remove the valve h' from its seat, when the oil will pass freely through the annular space between the rod H and the branch B; thence along the grooves i through the opening in the block C, and thence through the opening d into the cylinder, steam-chest, or other part of the engine to be lubricated.

It will now be seen without further description that by simply moving the handle F first in one direction and then in another

the oil is first admitted to and then discharged from the reservoir—an operation which in ordinary oil-cups could only be accomplished by a complicated and costly system of stop-cocks.

The object of the chamber *y* and openings *g* is to permit the free egress of air upward from the interior of the hollow spindle *D* and reservoir *A* through the annular space between the interior of the spindle *D* and tube *f*, and thereby insure the free flow of oil into the reservoir.

I claim as my invention and desire to secure by Letters Patent—

1. A reservoir, *A*, hollow screw-spindle *D*, rod *H*, and any suitable spring for raising said rod, and the valve herein described, the whole being constructed and arranged, sub-

stantially as set forth, for admitting oil to and discharging it from the reservoir by the simple turning of the said spindle *D*.

2. The cup *G*, with its oil-receptacle *x*, air-chambery, and tube *f*, constructed and applied to the hollow spindle *D*, substantially as and for the purpose herein set forth.

3. The combination of the hollow block *C*, spring *M*, and grooves *i* at the bottom of the rod *H*.

In testimony whereof I have signed my name to this specification in the presence of two subscribing witnesses.

ROBERT ROSS.
